UNITED STATES PATENT OFFICE.

JOHN WARREN, OF BOSTON, MASSACHUSETTS, ASSIGNOR TO HIMSELF, AND DANIEL A. WHITE AND CHARLES F. CASEY, TRUSTEES, BOTH OF NEWTON, MASSACHUSETTS.

BOOT-TREEING MACHINE.

SPECIFICATION forming part of Letters Patent No. 289,044, dated November 27, 1882.

Application filed March 23, 1883. (No model.)

To all whom it may concern:

Be it known that I, JOHN WARREN, of Boston, in the county of Suffolk and State of Massachusetts, have invented certain new and useful Improvements in Boot-Treeing Machines, of which the following, taken in connection with the accompanying drawings, is a specification.

My invention relates to a machine for rubbing the exterior surfaces of boot-uppers in the operation technically known as "treeing;" and it consists in the employment of certain novel devices and combinations and arrangements of parts, which will be readily understood by reference to the description of the drawings, and to the claims, to be hereinafter given.

Figure 1 of the drawings illustrates a sectional elevation of a machine embodying my invention, the right-hand half of said figure representing an elevation with the shank-rubbing wheel removed, and the left-hand portion representing a central vertical section in a plane at right angles to the wheel-shaft. Fig. 2 is a central vertical section in a plane through the axis of the wheel-shaft. Fig. 3 is a partial section on line $x-x$ on Fig. 1, showing the position of one of the flexible rubbers when in operation upon a boot-leg with the "tree" therein; and Fig. 4 represents an elevation of the shank-rubbing wheel with the leather covering removed from the right-hand half thereof.

A is a column, provided with the base-flange A', and the two upwardly-projecting arms A² A³, in the upper ends of which are formed the bearings A³ A³, in which is mounted the shaft B, having firmly secured upon one end the driving-pulley C and upon the other end the shank-rubbing wheel D, as shown.

E E are two disks or wheels fitted to the shaft B, between the bearings A³ A³, in such a manner that they may be moved toward and from each other upon said shaft, while they are compelled to revolve therewith. The hubs of the wheels E E have set therein keys or feathers a, which also fit into and slide in grooves formed in the shaft B in a well-known manner.

F is a spiral spring surrounding the shaft B, between the hubs of the wheels E E, and

acting thereon by its tension to force said wheels apart.

G G are two rings fitted loosely upon the shaft B, outside of the wheels E, each in close proximity to the hub of one of said wheels, and pivoted to the upper end of one of the elbow shipper-levers H H, which levers are pivoted at b b to ears c, formed upon the inner sides of the arms A² A³, and forked at their upper ends, and provided with pivotal pins or centers d to receive the rings G G, as partially shown in Fig. 1. The lever-arms of the shipper-levers H H project inward or toward each other till they nearly meet, and are connected by the links e e and rod f to the treadle I, pivoted by its rear end within the column A, and projecting through the slot g, cut through the front side of the column A, as shown.

J is a pawl-lever pivoted to the treadle-lever I, and arranged to engage with the ratchet-teeth h, formed upon the column A, on each side of the slot g, for the purpose of retaining the wheels E E at the required distance apart when they are moved inward by depressing the treadle-lever I, to adapt them to any particular job.

A series of leather tubes, K, are arranged at regular and equal distances from each other around the peripheries of the wheels E E, with their central portions curved inward toward the shaft B, and their end portions radial thereto, said tubes being bent around grooved pulleys i i, mounted in slots formed in the peripheries of said wheels, and each being connected at each end to a spring, j, the other end of which is connected to a pin set in the hub of the wheel E, as shown in Fig. 2. The leather tubes K are filled with a core, k, of some flexible material—such as a cord of leather or textile material or powdered soapstone—and have secured to each end thereof a metallic coupling, L, composed of the sleeve l and plug l', the latter being provided with the eye m, as a means of connecting the spring j thereto, and screwed into the sleeve l, as shown. The greater part of the lengths of the sleeve l and plug l' are made tapering, or in the form of frustums of cones, and the conical periphery of the plug l' is roughened by forming thereon a screw-thread adapted to

press into the leather of the tube K without cutting it, as shown in Fig. 2.

The pulleys *i i* are provided with journals which rest in slots formed in the edges of the ribs *m'* of the wheels E E, and said pulleys are prevented from leaving said bearings, in case of the breakage of a tube K while the wheels E are in motion, by caps or guards over said journals, as shown at *n* in Fig. 1.

10 An endless band or hoop, M, is fitted closely to and secured upon the periphery of each of the wheels E, as shown in Figs. 1 and 2, for the purpose of preventing the tubes K from being displaced from the pulleys *i i*, said hoops being made preferably of metal and covered with leather.

The shank-rubbing wheel D consists of a plain circular metal disk, *n'*, provided with a suitable central hub, and means of securing it firmly to the shaft B, and having cast upon its outer radial face a series of lugs, *n² n²*, upon each of which is secured a block of wood, *o*, the outer face of which is curved to the desired shape, as shown in Fig. 2.

25 The blocks of wood *o* and the lugs *n'*, with the beveled periphery of the disk, are covered with leather *o'*, which is first molded to the desired shape, then placed in position on the wheel D and secured thereto by the metal clamping-rings *p* and *q*, secured to the wheel by suitable screws, as shown in Figs. 2 and 4.

The operation of my invention is as follows: The boot being stretched upon the ordinary tree, the operator takes it in his hand and, 35 holding it in the desired position in contact with one or more of the leather rubbing cords or tubes K, sets the shaft B in motion, to cause the wheels E E to revolve and bring each of the flexible rubbers K into action upon the 40 boot in succession, the operator meanwhile placing his foot upon the treadle-lever I to depress it, and thus move the wheels E E toward each other, and cause the flexible rubbers K K to be bent around the boot to a greater or less 45 extent as he presses the boot toward the axis of the shaft B, and at the same time turning the boot in his hands, as may be required to present all parts of the boot-upper that can be touched by the rubbers K into position to be 50 acted upon thereby.

In order to finish those portions of the upper in proximity to the sole-edge along the shank and fore part of the boot, the operator applies those parts of the boot to the action of 55 the wheel D. By this means all parts of the boot may be acted upon by the machine, and

the treeing may be completed without other hand-work than placing the boot upon and removing it from the tree.

What I claim as new, and desire to secure 60 by Letters Patent of the United States, is—

1. In a machine for treeing boots, one or more flexible rubbers in the form of round cords or bands, arranged in planes radial to, and extending longitudinally of, and adapted 65 to be revolved about an axis of motion, and to be bent or wrapped partially around the boot by contact therewith, substantially as described.

2. In a machine for treeing boots, a series 70 of flexible rubbers in the form of round leather cords or straps, arranged in radial planes around and equidistant from a common axis, about which they may be revolved, and adapted to be brought successively into contact with 75 the boot to be treed, and to be bent partially around said boot by contact therewith, substantially as described.

3. The combination of the shaft B, the wheels E E, the series of flexible leather rubbers K K, 80 the two series of springs *j*, the two series of pulleys *i i*, and means of imparting to the shaft B and wheels E E a rotary motion, substantially as described.

4. The combination of the shaft B, the wheels 85 E E, arranged to revolve therewith, and to be moved endwise thereon, the flexible rubbers K K, the pulleys *i i*, the springs *j j*, and mechanism for moving the wheels E E toward and from each other, substantially as and for the 90 purposes described.

5. The combination of the shaft B, the wheels E E, a series of flexible rubbers, K K, a series of pulleys, *i i*, a series of springs, *j j*, the spring F, the two shipper-levers H H, connected to 95 and adapted to move said wheels E E toward each other, the treadle-lever I, and means of connecting said treadle to the levers H H, substantially as described.

6. The wheel D, composed of the metal disk 100 *n'*, provided with the lugs *n² n²*, the wooden blocks *o o*, leather covering *o'*, and the clamping-rings *p* and *q*, all arranged and combined substantially as described.

In testimony whereof I have signed my 105 name to this specification, in the presence of two subscribing witnesses, on this 20th day of March, A. D. 1883.

JOHN WARREN.
